INVENTOR.

W. H. Rice

BY
Philip A. G. Lowell
ATTORNEY.

UNITED STATES PATENT OFFICE.

WILLIAM H. RICE, OF OMAHA, NEBRASKA.

NEEDLE THREADER.

Application filed December 19, 1924. Serial No. 756,911.

To all whom it may concern:

Be it known that WILLIAM H. RICE, a citizen of the United States, residing at Omaha, in the county of Douglas and State of Nebraska, has invented certain new and useful Improvements in Needle Threaders, of which the following is a specification.

The invention relates to needle threading devices, and has for its object to provide a device of this character which is simple in construction, positive in its operation and constructed in a manner whereby a needle may be easily and quickly threaded by a person with defective or failing eyesight, who are particularly in need of a convenient and positive means for threading a needle.

A further object is to provide a needle threading device comprising a hollow base having vertically disposed rod slidably mounted therein, and with which coiled springs, within the hollow base, cooperate for forcing the same upwardly. The upper ends of the rods have connected thereto and disposed therebetween a block having right angularly disposed V-shaped recesses extending entirely across the same, in one of which the eye of the needle is received after the thread has been longitudinally disposed in the other V-shaped recess, and to provide the hollow base with an upwardly extending relatively flat arm, slidably mounted in a vertically disposed aperture extending through the block and having its upper end located, whereby upon a downward movement of the block against the action of the rod springs said upper end of the relatively flat member will force a bight of the thread through the eye of the needle.

A further object is to provide flat thread gripping fingers carried by the rods for gripping and holding the thread frictionally during the operation of the device, and in a manner whereby the thread will slip during the forcing of the bight thereof through the eye of the needle.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

55 In the drawing:—

Figure 1 is a perspective view of the needle threading device.

Figure 2 is a top plan view of the slidable block.

Figure 3 is a side elevation of the needle 60 threading device.

Figure 4 is a front elevation of the needle threading device.

Referring to the drawing, the numeral 1 designates the hollow base of the needle 65 threading device, which base is provided in the chamber 2 thereof with a horizontally disposed partition 3. Slidably mounted in the partition 3, and in the removable top plate 4 of the casing are parallel vertically 70 disposed rods 5, which rods extend upwardly a substantial distance above the casing 1, and are secured by means of rivets 6 to opposite sides of a needle and thread receiving block 7, which block when forced downwardly 75 forces the rod 5 downwardly, thereby compressing the springs 8, which surround the rods 5, within the chamber 2 of the casing, and which springs are interposed between the pins 9 carried by the rods and the partition 3.

Extending upwardly from the top 4 of the casing 1 is a relatively flat member 10 which is in parallel relation to the rod 5 and disposed therebetween, and which flat 85 member is slidably mounted in an aperture 11 extending vertically through the block 7. Block 7 has its upper end provided with a transversely disposed V-shaped recess 12, in which the eye end 13 of the needle 14 is 90 placed when it is desired to force the thread 15 through the eye 16 of the needle, and which thread extends through the longitudinal V-shaped recess 17 of the block at a right angle to the recess 12. The thread 12 95 is held at opposite sides of the block 7 by means of leaf springs 18 which are secured to the forward sides of the rods 5 at 19, however the leaf springs 18 frictionally hold the thread, but at the same time allow the 100 thread to slip during the needle threading operation when the block 7 is forced downwardly by the operator upon a downward pressure on the needle 14, and which action will force the relatively flat member 10 upwardly through the eye 16 of the needle, thereby carrying the bight 20 of the thread 15 105 through the eye, after which the downward pressure on the block is released, which allows the springs 8 to force the block up-

110

wardly for removing the flat member 10 from the eye, or the bight can be grasped before the block is released for pulling the thread further through the eye of the needle.

5 From the above it will be seen that a needle threading device is provided which is simple in construction, the parts reduced to a minimum and the device constructed in a manner whereby it may be cheaply manufactured and sold. The cover is preferably held on the upper end of the casing 1 by means of spring arms 21 which cooperate with lugs 22 carried by the casing 1, and by providing the cover 4, it is obvious that access may be had to the interior of the casing for assembling or repair purposes.

The invention having been set forth what is claimed as new and useful is:—

1. A needle threading device comprising a hollow casing, a horizontally disposed partition in said casing, vertically disposed parallel rods slidably mounted in said partition and casing, springs surrounding the rods within the casing and normally forcing said rods upwardly, a needle receiving block disposed between said rods above the casing and secured to the rods, a vertically disposed thread engaging arm carried by the upper end of the casing between the rods

and extending through a vertically disposed 30 aperture in the block, a needle receiving recess carried by the upper end of the block and with which the aperture communicates, a thread receiving recess at a right angle to the needle receiving recess and spring thread 35 gripping arms carried by the forward sides of the rod at opposite sides of the block.

2. A needle threading device comprising a casing having a chamber therein, spaced parallel vertically disposed slidable rods 40 mounted in bearings of the casing, springs disposed within the casing and cooperating with the rods for simultaneously forcing the same upwardly, a needle receiving block secured to the upper ends of the rods above 45 the casing, right angularly disposed needle and thread receiving recesses in the upper end of the block, a needle engaging arm carried by the upper end of the casing between the rods and extending vertically through an 50 aperture in the block and adapted to move upwardly through the upper end of the block at the point of intersection of the needle and thread recesses and spring thread gripping arms carried by the rods at opposite 55 sides of the block.

In testimony whereof I affix my signature.
WILLIAM H. RICE.
